TWO-STAGE PRETREATMENT OF REFORMER
CHARGE NAPHTHAFrancis Earle Davis, Jr., Westville, and Amilcare Ramella,
Woodbury, N.J., assignors to Socony Mobil Oil Com-
pany, Inc., a corporation of New YorkFiled July 16, 1958, Ser. No. 748,901
7 Claims. (Cl. 208—254)

The present invention relates to the pretreatment of naphtha to be reformed over a nitrogen-sensitive catalyst and, more particularly, to the pretreatment of naphtha containing nitrogen compounds under relatively mild conditions prior to reforming the pretreated naphtha over a nitrogen-sensitive catalyst of the platinum type.

For several years it has been common practice to hydrodesulfurize naphtha prior to reforming the naphtha. In some instances the hydrodesulfurization of the naphtha was to eliminate poisoning of the reforming catalyst but in most instances the hydrodesulfurization of the naphtha was to reduce corrosion of the reforming unit or to reduce the size of the facilities required to remove the sulfur compounds from gases vented to the air.

Prior to the increased demand for high octane gasoline it was unnecessary to reform many stocks containing high concentrations of organic nitrogen compounds which poison nitrogen-sensitive catalysts such as the platinum-type reforming catalysts. With the increased demand for high octane gasoline it has become necessary to reform many of those stocks which until recently were not reformed.

Hydrodesulfurization of practically all common naphthas can be carried out under relatively mild conditions of temperature, pressure and hydrogen-to-naphtha ratio and at a relatively high space velocity. Thus, for example, a straight run naphtha from a Kuwait crude containing about 800 parts per million (p.p.m.) of sulfur and 0.2 p.p.m. of nitrogen can be hydrodesulfurized and hydrodenitrogenized over a catalyst comprising a mixture of oxides of cobalt and molybdenum on alumina at about 675° F. under about 425 p.s.i.g. at a hydrogen-to-naphtha ratio of about 500 standard cubic feet (s.c.f.) of hydrogen per barrel of naphtha charged and at a space velocity (volume of naphtha/hour/volume of catalyst, v./hr./v.) of about 5 to provide a reformer charge stock containing less than 20 p.p.m. sulfur and substantially devoid of nitrogen compounds. On the other hand, when a mixture comprising about 15 percent by volume of thermal gasoline containing 66 p.p.m. of nitrogen and about 85 percent by volume of straight run naphtha containing about 0.2 p.p.m. of nitrogen is hydrodecontaminated over the same catalyst under the same operating conditions the nitrogen content of the hydrodecontaminated mixture is reduced from 10 p.p.m. to 1.4 p.p.m.

It has been found that to maintain a platinum-type reforming catalyst on stream for a practical period of time the nitrogen content of the charge to the reforming reactor must be less than about 1 p.p.m. of nitrogen.

It has also been determined that to reduce the nitrogen content of a naphtha containing about 12 p.p.m. of nitrogen to less than 1 p.p.m. of nitrogen requires much more severe conditions than the aforescribed mild conditions. Thus, a naphtha containing 12 p.p.m. of nitrogen can be hydrodecontaminated to a nitrogen content of less than 1 p.p.m. over a catalyst comprising a mixture of oxides of cobalt and molybdenum on alumina at a temperature of 775° F., pressure of 425 p.s.i.g., hydrogen-to-naphtha ratio of about 2000 s.c.f./barrel of naphtha charged and a space velocity of 2.

2

It has now been determined that when a naphtha having a high nitrogen content, i.e., in excess of 25 p.p.m. of nitrogen is first hydrodecontaminated under relatively mild conditions such as set forth hereinbefore and more particularly as described hereinafter, the treated naphtha stripped of volatile nitrogen compounds, and the stripped treated naphtha mixed with low nitrogen containing naphtha to provide a blend having not more than about 7 p.p.m. and the mixture hydrodecontaminated under relatively mild conditions as set forth hereinbefore and more particularly as described hereinafter, the hydrodecontaminated mixture will contain less than 1 p.p.m. of nitrogen.

Illustrative of the treatment of a high nitrogen naphtha containing in excess of 25 p.p.m. of nitrogen is the flow-sheet of FIGURE 1. The flowsheet of FIGURE 1 illustrates the treatment of a naphtha having a high concentration of nitrogen, to wit: Thermal naphtha containing 66 p.p.m. of nitrogen, over a catalyst combining capabilities of hydrogenate, hydrodesulfurize and hydrodenitrogenize, e.g., a mixture of oxides of cobalt and molybdenum. The partially hydrodecontaminated naphtha is stripped of volatile hydrogen derivatives of the contaminants, and the stripped, partially hydrodecontaminated naphtha containing about 24 p.p.m. of nitrogen is then mixed with a naphtha having a low nitrogen content, e.g., about 0.2 p.p.m. to provide a mixture containing about 3 p.p.m. of nitrogen. The mixture is hydrodecontaminated and stripped of volatile hydrogen derivatives of the contaminants to provide a reformer feed containing about 0.3 p.p.m. of nitrogen and less than 20 p.p.m. of sulfur. The naphtha feed thus produced is then reformed over a nitrogen-sensitive catalyst, e.g., a platinum-type catalyst comprising about 0.1 to about 1 percent platinum on alumina.

In FIGURE 1 a naphtha containing in excess of 25 p.p.m. of nitrogen, e.g., thermal naphtha containing about 66 p.p.m. nitrogen, is drawn from a source not shown through pipe 1 by pump 2. Pump 2 discharges the thermal naphtha containing about 66 p.p.m. of nitrogen into conduit 3 at a pressure in excess of the pressure in secondary decontaminator 10. It is preferred to mix about 50 to about 100 cubic feet (c.f.) of hydrogen per barrel of thermal naphtha with the naphtha prior to heating the naphtha to hydrodecontaminating temperature. Accordingly, hydrogen-rich recycle gas flowing from conduit 9 under control of valve 84 flows through conduit 85 to conduit 3. The mixture of thermal naphtha and the small amount of hydrogen flows through conduit 3 to heat exchanger 4 where the thermal naphtha is in indirect heat exchange relation with the effluent of the secondary decontaminator 10 flowing through conduit 11.

From heat exchanger 4 the thermal naphtha and the small amount of hydrogen flow through conduit 5 to coil 6 in heater 7. In coil 6 the thermal naphtha is heated to a hydrodecontaminating temperature within the range of about 600° to about 850° F. The heated thermal naphtha and hydrogen flow from coil 6 through conduit 8 to conduit 9. In conduit 9 the thermal naphtha is mixed with additional hydrogen to provide a total of about 500 to about 2500 s.c.f. of hydrogen per barrel of thermal naphtha. For this purpose hydrogen-rich gas drawn from liquid-gas separator 17 and stripper 24 by compressor 29 as hereinafter described and discharged into conduit 9 is used. The heated thermal naphtha and hydrogen-containing gas flow through conduit 9 to secondary decontaminator 10.

In secondary decontaminator 10 the treating conditions for a cobalt molybdenum catalyst are within the limits set forth in Table I.

3

Table I

Catalyst: 2 to 3 percent cobalt oxide, 9 to 16 percent molybdenum oxide on alumina.
Feed: Thermal naphtha containing 66 p.p.m. nitrogen.

	Broad	Preferred
Temperature, ° F.....	600-850	675-775
Pressure, p.s.i.g.....	260-1,000	400-800
S.c.f. H ₂ /barrel of naphtha ¹	500-2,500	800-1,000
Space velocity, v./hr./v.....	1-10	2.5-5

¹ S.c.f. is standard cubic feet.

The thermal naphtha and hydrogen-containing recycle gas pumped from separator 17 and stripper 24 by compressor 29 at a pressure higher than that in the secondary decontaminator 10 flow downwardly through the secondary decontaminator to conduit 11. The partially decontaminated thermal naphtha and recycle gas, hereinafter designated secondary effluent, flow through conduit 11 to heat exchanger 4 where the secondary effluent is in indirect heat exchange relation with the thermal naphtha feed as described hereinbefore.

The secondary effluent flows from heat exchanger 4 through conduit 12 to heat exchanger 13 where the secondary effluent is in indirect heat exchange relation with the secondary condensate pumped from liquid-gas separator 17 by pump 21 through pipe 22. The cooled secondary effluent flows from heat exchanger 13 through conduit 14 to cooler 15 where the temperature of the secondary effluent is lowered to that at which C₄ and heavier hydrocarbons are liquid at the pressure existing in liquid-gas separator 17.

From cooler 15 the secondary effluent flows through conduit 16 to liquid-gas separator 17. In liquid-gas separator 17 the uncondensed portion of the secondary effluent separates from the condensed portion of the secondary effluent. The uncondensed portion of the secondary effluent flows from separator 17 through conduit 18 to conduit 19.

The condensed portion of the secondary effluent flows through pipe 20 to pump 21. Pump 21 discharges the condensed portion of the secondary effluent, hereinafter designated secondary condensate, into pipe 22 through which the secondary condensate flows to heat exchanger 13 where it is in indirect heat exchange relation with the secondary effluent. From heat exchanger 13 the secondary condensate flows through pipe 23 to stripper 24.

The secondary condensate is stripped of volatile hydrogen derivatives of the contaminants sulfur, nitrogen, arsenic, etc., originally present in the thermal naphtha in stripper 24. Preferably a stripping gas e.g., hydrogen-containing gas from the primary liquid-gas separator 53 and/or the primary stripper 60 and/or recycle gas from a reformer unit flowing through conduit 74 as more fully discussed hereinafter is used to assist in stripping the volatile hydrogen derivatives of the contaminants present in the thermal naphtha feed from the secondary condensate. The volatile hydrogen derivatives of the aforesaid contaminants, together with light hydrocarbons and stripping gas are taken as overhead through conduit 19. The overhead from stripper 24 flows through conduit 19 and together with the uncondensed portion of the secondary effluent flowing from separator 17 through conduit 18 (as described hereinbefore) flows to any suitable means 25 for removing the hydrogen derivatives of nitrogen compounds originally present in the thermal naphtha, to wit, ammonia. For example, the gaseous mixture can be contacted with aqueous acid, for example, sulfuric acid, to remove the ammonia. From the means 25 to remove ammonia the gaseous mixture flows through conduit 26 to means 27, such as an amine scrubber, for removing hydrogen sulfide (the hydrogen derivative of sulfur compounds originally present in the thermal naphtha). Hydrogen sulfide removal means 27 can be by-passed by closing valve 86 and opening valve 88 in conduit 89.

4

From means 27 the purified gaseous mixture designated secondary recycle gas and containing about 50 to about 95 percent hydrogen flows through conduit 28 to the suction side of compressor 29. Any gas in excess of that required in the secondary decontaminator is vented from conduit 28 through conduit 30 under control of valve 31 for use in other processing or to the refinery fuel system. Compressor 29 discharges the secondary recycle gas into conduit 9 as described hereinbefore.

Returning now to stripper 24, the stripped secondary condensate forms a bottoms in stripper 24. A minor portion of the bottoms of stripper 24 flows from stripper 24 through pipe 32 to heat exchanger 33 and from heat exchanger 33 through pipe 34 back to stripper 24. In heat exchanger 33 the bottoms is heated to a temperature at which under conditions in the stripper 24 the hydrogen derivatives of the contaminants originally present in the thermal gasoline are volatilized. Any other means for maintaining the necessary stripping temperature can be used instead of the reboiler shown.

The major portion of the stripper bottoms flows from stripper 24 through pipe 35 to the suction side of pump 36. Pump 36 discharges the bottoms of stripper 24 into pipe 37.

The bottoms of stripper 24 usually contains not more than about 140 p.p.m. of nitrogen. In the illustrative case in which the thermal naphtha feed contained 66 p.p.m. of nitrogen and 1,700 p.p.m. of sulfur the stripper bottoms contained about 24 p.p.m. of nitrogen and about 82 p.p.m. of sulfur.

Prior to treatment in the primary decontaminator the stripper bottoms is mixed with a low nitrogen naphtha such as a straight run naphtha containing about 0.1 to about 1 p.p.m. of nitrogen. In the illustrative case a straight run naphtha containing about 0.2 p.p.m. of nitrogen was mixed with the bottoms of stripper 24 in proportions to provide a primary decontaminator feed containing not more than about 7 p.p.m. of nitrogen. In the illustrative case the stripper bottoms and straight run naphtha were mixed in the proportions indicated in Table II.

Table II

	Percent by Volume	P.p.m. Nitrogen	P.p.m. Nitrogen in Mixture
Stripper bottoms.....	15	24	3.6
Straight run naphtha.....	85	0.2	0.17
Total.....			3.77

Accordingly, straight run naphtha drawn from a source not shown through pipe 38 by pump 39 is pumped through pipe 40 to heat exchanger 41. In heat exchanger 41 the straight run naphtha is in indirect heat exchange relation with primary effluent flowing from primary decontaminator 46 through conduit 47. From heat exchanger 41 the straight run naphtha flows through pipe 42 to pipe 37 where it is mixed with the stripper bottoms to provide a mixture containing about 50 to about 95 percent by volume straight run naphtha, said mixture containing not more than about 7 p.p.m. of nitrogen. The mixture of stripper bottoms and straight run naphtha, hereinafter designated primary decontaminator feed flows through pipe 37 to coil 43 in heater 44. It is preferred to mix a small amount, say about 50 to about 100 s.c.f. of hydrogen-containing gas such as primary recycle gas pumped by compressor 67 through conduits 68 and 69 under control of valve 70 with the primary decontaminator feed prior to heating the primary decontaminator feed to reaction temperature. The primary decontaminator feed and primary recycle gas are heated in heater 44 to a temperature within the range of about 600 to about 850° F. From coil 43 the primary decon-

taminator feed and hydrogen flow through conduit 45 to primary decontaminator 46. In conduit 45 additional hydrogen-containing gas, such as primary recycle gas, pumped by compressor 67 through conduit 68 is mixed with the primary decontaminator feed in amount sufficient to provide a total of about 250 to about 1000 s.c.f. of hydrogen per barrel of primary decontaminator feed. The mixture of primary decontaminator feed and primary recycle gas flows downwardly through primary decontaminator 46 to conduit 47.

The operating conditions in primary decontaminator 46 are substantially the same as in secondary decontaminator 10 and are mild operating conditions. For a catalyst having hydrogenating as well as decontaminating capabilities such as a catalyst comprising about 3 percent cobalt oxide and about 12 percent molybdenum oxide on alumina the operating conditions in primary decontaminator 46 are as set forth in Table III.

Table III

Catalyst: 2 to 3% cobalt oxide, 9 to 16% molybdenum oxide. Feed: not more than 7 p.p.m. of nitrogen.

	Broad	Preferred
Temperature, ° F-----	600 to 850	675 to 775
Pressure, p.s.i.g-----	200 to 1,000	400 to 500
Hydrogen, s.c.f./bbl. of naphtha-----	250 to 2,500	400 to 600
Space Velocity, v.bhr./v.-----	1 to 10	2.5 to 5.0

From primary decontaminator 46 the effluent, designated primary effluent hereinafter, flows through conduit 47 to heat exchanger 41 where the primary effluent is in indirect heat exchange relation with the straight run naphtha as previously described. From heat exchanger 41 the primary effluent flows through conduit 48 to heat exchanger 49 where the primary effluent is in indirect heat exchange relation with the condensed portion of the primary effluent designated primary condensate flowing from liquid-gas separator 53. From heat exchanger 49, the primary effluent flows through conduit 50 to cooler 51. In cooler 51 the primary effluent is cooled to a temperature at which C₄ and heavier hydrocarbons condense at the pressure existing in liquid-gas separator 53. The cooled primary effluent flows from heat exchanger 51 through conduit 52 to liquid-gas separator 53. In liquid-gas separator 53 the uncondensed portion of the primary effluent separates from the condensed portion of the primary effluent (hereinafter designated primary condensate) and flows from separator 53 through conduit 54 to conduit 55.

The primary condensate flows from separator 53 through pipe 56 to the suction side of pump 57. Pump 57 discharges the primary condensate into pipe 58 through which the primary condensate flows to heat exchanger 49. In heat exchanger 49 the primary condensate is in indirect heat exchange relation with the primary effluent as hereinbefore described. From heat exchanger 49 the primary condensate flows through pipe 59 to stripper 60.

In stripper 60 the primary condensate is stripped of hydrogen derivatives of contaminants present in the primary feed, light hydrocarbons and residual hydrogen, preferably with aid of a stripping gas such as hydrogen-containing gas, for example, reformer recycle gas, pumped from a reformer unit not shown through conduit 61. An overhead comprising the hydrogen derivatives of contaminants present in the primary feed such as ammonia and hydrogen sulfide, hydrogen and light hydrocarbons, hereinafter designated primary recycle gas, is taken from stripper 60 through conduit 62 to conduit 55. The overhead flows through conduit 55 to means 63 of any suitable type, as for example contact with aqueous acid solution, for removing ammonia. Hydrogen sulfide removal means 65 can be by-passed by closing valves 90 and 91 and opening valve 92 in conduit 93. From the means 63 for removing ammonia, the overhead flows through

conduit 64 to means for removing hydrogen sulfide 65, for example, an amine scrubber. From the means for removing hydrogen sulfide 65 the primary recycle gas flows to the suction side of compressor 67. Compressor 67 discharges the hydrogen-containing primary recycle gas into conduit 68. A small portion, say about 50 to about 100 s.c.f., of primary recycle gas is diverted through conduit 69 under control of valve 70 to conduit 37 for the purpose of mixing the primary recycle gas with the primary decontaminator feed as described hereinbefore. The balance of the primary recycle gas flows through conduit 68 to conduit 45 where it is mixed with the primary decontaminator feed in amounts to provide a total of about 250 to about 2500 s.c.f. of hydrogen per barrel of primary decontaminator feed as described hereinbefore.

As stated hereinbefore, the stripping gas for stripping the secondary decontaminator condensate is either a portion of the overhead from stripper 60 or reformer recycle gas or a mixture of both. Thus, when overhead from stripper 60 is to be used to strip the secondary decontaminator condensate in stripper 24 about 300 to about 500 s.c.f. of overhead from stripper 60 per barrel of high nitrogen feed naphtha flows from conduit 55 through conduit 71 under control of valve 72 to compressor 73. Compressor 73 discharges the overhead from stripper 60 hereinafter designated secondary stripping gas into conduit 74. The secondary stripping gas flows through conduit 74 to stripper 24. When it is necessary or desirable to use reformer recycle gas as stripping gas the required amount of reformer recycle gas is diverted from conduit 61 through conduit 75 under control of valve 76 to conduit 74 through which the reformer recycle gas flows to stripper 24. It follows that a mixture of secondary stripping gas from conduit 55 and reformer recycle gas can be used to strip the secondary decontaminator condensate in stripper 24 by opening both valves 76 and 72 the required amounts to proportion secondary stripping gas and reformer recycle gas as is necessary or desirable. In the event that either secondary stripper 24 or primary stripper 60 operates or both operate at pressures higher than that at which reformer recycle gas is available the pressure of the reformer recycle gas can be raised to that of stripper 24 without raising the pressure of the reformer recycle gas flowing to stripper 60 by opening valve 77. The portion of the reformer recycle gas required in stripper 24 is diverted under control of valve 77 through conduit 78 to the suction side of compressor 79. Compressor 79 discharges into conduit 80. With valves 83 and 76 closed, the portion of the reformer recycle gas diverted to compressor 79 flows from conduit 80 to conduits 75 and 74 to stripper 24. When both stripper 60 and stripper 24 are operating at pressures higher than that at which the reformer recycle gas is available valve 81 is closed, valve 77 is opened and the total flow of reformer recycle gas is passed through conduit 78 to compressor 79. With valve 83 open and valve 76 closed the discharge of compressor 79 flows through conduits 61, 80 and 82 to stripper 60 and through conduits 80, 75 and 74 to stripper 24.

The flowsheet, FIGURE 2, illustrates another embodiment of the present invention wherein the secondary condensate is freed from a major portion, if not all, of the ammonia produced in hydrodecontaminating a naphtha having a high nitrogen content, i.e., in excess of 25 p.p.m. of nitrogen.

Thus, a hydrocarbon mixture such as a thermal naphtha, e.g., a coker naphtha containing in excess of 25 p.p.m. of nitrogen is drawn from a source not shown by pump 101 through pipe 102. Pump 101 discharges the hydrocarbon mixture containing in excess of 25 p.p.m. of nitrogen, hereinafter designated nitrogenous hydrocarbon mixture, into pipe 103. The nitrogenous hydrocarbon mixture flows through pipe 103 to heat exchanger 104 where it is in indirect heat exchange relation with the

effluent from the secondary decontaminator, hereinafter designated secondary effluent, flowing from secondary decontaminator 110 through conduit 111. From heat exchanger 104 the nitrogenous hydrocarbon mixture flows through pipe 105 to coil 106 in furnace 107 where it is heated to reaction temperature as described hereinbefore. When desirable, a small amount, say about 50-100 s.c.f. per barrel, of hydrogen-containing gas, e.g., primary recycle gas flowing in conduit 109 can be mixed with the nitrogenous hydrocarbon mixture prior to introduction of the nitrogenous hydrocarbon mixture into coil 106.

From heater 107 the heated nitrogenous hydrocarbon mixture flows through pipe 108 to secondary decontaminator 110. At some point in pipe 108 intermediate to heater 107 and to decontaminator 110 hydrogen-containing gas containing not more than about 0.02 percent ammonia, e.g., primary recycle gas flowing from separator 147 through conduits 148 and 149 to means for removing ammonia 159 and thence through conduit 169 to pipe 108 is mixed with the nitrogenous hydrocarbon mixture in an amount to provide about 500 to about 2500 s.c.f. of hydrogen per barrel of nitrogenous hydrocarbon mixture.

The mixture of hydrogen-containing gas and nitrogenous hydrocarbon mixture flows downwardly through secondary decontaminator 110. The secondary effluent flows from secondary decontaminator 110 through conduit 111 to heat exchanger 104 where the secondary effluent is in indirect heat exchange relation with the nitrogenous hydrocarbon mixture as described hereinbefore. From heat exchanger 104 the secondary effluent flows through conduit 112 to heat exchanger 113 where the secondary effluent is in indirect heat exchange relation with the condensate drawn from gas-liquid separator 117 through pipe 120 by pump 121 and discharged into pipe 122. From heat exchanger 113 the secondary effluent flows through pipe 114 to cooler (condenser) 115 where the secondary effluent is cooled to a temperature at which at the existing pressure the C₄ and heavier hydrocarbons are condensed. The cooled secondary effluent flows from cooler 115 through conduit 116 to gas-liquid separator 117.

In separator 117 the uncondensed portion of the secondary effluent comprising ammonia, hydrogen sulfide, C₃ and lighter hydrocarbons, and hydrogen separates from the condensed portion of the secondary effluent and flows through conduit 118 to conduit 119 and thence to means for removing ammonia 168 and thence through conduit 169 to means for removing hydrogen sulfide (not shown) and thence to an absorber (not shown) where the uncondensed secondary effluent is contacted with hydrocarbon mixture to be hydrodecontaminated. The condensed portion of the secondary effluent, hereinafter designated secondary condensate, flows from separator 117 through pipe 120 to the suction side of pump 121. Pump 121 discharges the secondary condensate into pipe 122. The secondary condensate flows through pipe 122 to heat exchanger 113 as described hereinbefore. From heat exchanger 113 the secondary condensate, heated to a temperature at which C₄ and lighter hydrocarbons are volatile, flows through pipe 123 to stripper 124. In stripper 124 the secondary condensate is contacted with stripping gas, e.g., hydrogen-containing gas from separator 147 flowing through conduits 148 and 167 or a mixture of gas from separator 147 and hydrogen-containing reformer gas flowing to stripper 124 through conduits 137, 154 and 167.

The overhead from stripper 124 comprising a major portion of C₄ hydrocarbons and lighter hydrocarbons together with hydrogen and substantially all of the hydrogen derivatives of contaminants present in the nitrogenous hydrocarbon mixture, e.g., ammonia and hydrogen sulfide, flows through conduit 125 to conduit 119 and to means 168 for removal of ammonia and then through conduit 169 to means for removing hydrogen sulfide (not shown)

and to an absorber where the overhead is contacted with hydrocarbons to be decontaminated.

5 A portion of the bottoms of stripper 124 flows through pipe 128 to heat exchanger 129 where the bottoms is heated to a temperature at which a major portion of the C₄ hydrocarbons is volatile. Any other means of maintaining the aforesaid temperature in stripper 124 can be used. From heat exchanger 129 the bottoms flows through pipe 130 back to stripper 124.

10 The balance, and major portion, of the bottoms of stripper 124 containing not more than about 140 p.p.m. of nitrogen flows therefrom through pipe 131 to the suction side of pump 132. Pump 132 discharges the stripper bottoms into pipe 133. At some point in pipe 133 intermediate to pump 132 and to coil 134 in heater 135 a hydrocarbon mixture having a nitrogen concentration such that, when mixed with the aforesaid stripper bottoms in the proportion of 50 to 95 parts by volume to 50 to 5 parts by volume of stripper bottoms, the mixture has a nitrogen concentration of not more than about 7 p.p.m., is mixed with the stripper bottoms. A suitable low nitrogen hydrocarbon mixture is straight run naphtha containing about 0.2 p.p.m. of nitrogen. Accordingly, straight run naphtha, for example, is drawn from a source not shown through pipe 160 by pump 161 and pumped through pipe 162 to heat exchanger 141. In heat exchanger 141 the straight run naphtha is in indirect heat exchange relation with the effluent from primary decontaminator 139. The effluent from primary decontaminator 139, hereinafter designated primary effluent, flows from decontaminator 139 to heat exchanger 141 through conduit 140. The straight run naphtha flows from heat exchanger 141 through pipe 172 to pipe 133 where the straight run naphtha is mixed with the stripper bottoms in a proportion to provide a mixture having a nitrogen content not greater than about 7 p.p.m.

20 The mixture, of stripper bottoms and straight run naphtha, containing not more than about 7 p.p.m. of nitrogen, hereinafter designated primary mixture, flows through pipe 133 to coil 134 in heater 135. The primary mixture is heated in coil 134 to a reaction temperature as set forth hereinbefore of about 600° to about 850° F. (Table III). From coil 134 the heated primary mixture flows through conduit 136 to primary decontaminator 139. At some 25 point in conduit 136 intermediate to heater 135 and to primary decontaminator 139 hydrogen-containing gas, for example, reformer gas is mixed with the primary mixture to provide about 250 to about 2500 s.c.f. of hydrogen per barrel of primary mixture. The primary mixture and hydrogen-containing gas flow downwardly through primary decontaminator 139 in contact with a catalyst having capabilities to hydrogenate and dehydrosulfurize and dehydrodenitrogenize the primary mixture. Illustrative of such catalysts is that described hereinbefore. The effluent 30 from primary decontaminator 139, hereinafter designated primary effluent, flows through conduit 140 to heat exchanger 141 where it is in indirect heat exchange relation with the straight run naphtha as previously described herein. From heat exchanger 141 the primary effluent flows through conduit 142 to heat exchanger 143 where the primary effluent is in indirect heat exchange relation with the condensate from separator 147 flowing to heat exchanger 143 through pipe 150.

35 From heat exchanger 143 the primary effluent flows through conduit 144 to cooler 145 where the primary effluent is cooled to a temperature at which C₄ and heavier hydrocarbons are condensed under the existing pressure. The condensed and uncondensed portions of the primary effluent flow from cooler 145 through conduit 146 to gas-liquid separator 147. In separator 147 the uncondensed portion of the primary effluent comprising hydrogen, ammonia, and light hydrocarbons separates from C₄ and heavier hydrocarbons and flows through conduit 148 to conduit 149, ammonia removal means 159, and conduits 109 and 108 to secondary 110 decontaminator as previous-

ly described hereinbefore. The C₄ and heavier hydrocarbons, hereinafter designated primary condensate, flow from separator 147 through pipe 150 to heat exchanger 143 as previously described. From heat exchanger 143 the primary condensate flows through pipe 151 to stripper 152.

In stripper 152 a major portion of the C₄ and lighter hydrocarbons together with residual amounts of hydrogen, hydrogen sulfide, and ammonia is taken overhead through pipe 153 to means 170 for removal of ammonia and then through conduit 171 to an absorber where the overhead is contacted with an absorbent for C₄ hydrocarbons.

A minor portion of the bottoms flows through a reboiler comprising pipe 164, heat exchanger 165 and pipe 166. The balance, and major portion, of the bottoms flows through pipe 163 to a reforming or other catalytic reaction unit employing a catalyst sensitive to more than 1 p.p.m. of nitrogen. In other words, the bottoms of stripper 152 contain not more than 1 p.p.m. of nitrogen.

The flow sheet presented as FIGURE 3 is illustrative of the hydrodecontamination of a hydrocarbon mixture containing more than 25 p.p.m. of nitrogen wherein the condensate from the gas-liquid separator is fractionated in a splitter to give an overhead containing C₅ and lighter hydrocarbons and dehexanized bottoms or a bottoms containing C₆ hydrocarbons as controlled by local conditions. Thus, a hydrocarbon mixture containing at least 25 p.p.m. of nitrogen, for example, a thermally cracked naphtha, hereinafter designated nitrogenous feed, is drawn from a source not shown through pipe 200 by pump 201. Pump 201 discharges the nitrogenous feed into pipe 202 at a pressure sufficient to force the nitrogenous feed through the downstream equipment. The nitrogenous feed flows through pipe 202 to heat exchanger 203 where the nitrogenous feed is in indirect heat exchange relation with the effluent from the secondary decontaminator flowing therefrom through conduit 210. From heat exchanger 203 the nitrogenous feed flows through pipe 204 to coil 205 in furnace or heater 206.

In heater 206 the nitrogenous feed is heated to a reaction temperature such as set forth hereinbefore. The heated nitrogenous feed flows from heater 206 through pipe 207 to secondary decontaminator 208. At some point in pipe 207 intermediate to heater 206 and to decontaminator 208 hydrogen-containing gas containing as little ammonia as practical is mixed with the heated nitrogenous feed in amount to provide about 500 to about 2500 s.c.f. of hydrogen per barrel of nitrogenous feed. A suitable hydrogen-containing gas for this purpose is the overhead from gas-liquid separator 257 flowing therefrom through conduits 258 and 259, means for removing ammonia 260 and conduits 261 and 209.

The mixture of nitrogenous feed and hydrogen-containing gas containing little or no ammonia, i.e., not more than about 0.02 percent by volume or 200 p.p.m. based upon the nitrogenous feed, flows downwardly through the catalyst bed in secondary decontaminator 208. The catalyst in secondary decontaminator 208 is one having hydrogenating capabilities combined with the capabilities of hydrodecontaminating, i.e., hydrodesulfurizing and hydrogenating hydrocarbon mixtures. Illustrative of such catalyst is that described hereinbefore.

The effluent of secondary decontaminator 208, herein-after designated secondary effluent, flows therefrom through conduit 210 to heat exchanger 203 where the secondary effluent is in indirect heat exchange relation with the nitrogenous feed as described hereinbefore. From heat exchanger 203 the secondary effluent flows through conduit 211 to heat exchanger 212 where the secondary effluent is in indirect heat exchange relation with the condensed hydrocarbons flowing from gas-liquid separator 216 through pipe 218 to pump 219 and thence through pipe 220 to heat exchanger 212. From heat exchanger 212 the secondary effluent flows through con-

duit 213 to cooler 214. In cooler 214 the secondary effluent is cooled to a temperature at which at the existing pressure, C₄ and heavier hydrocarbons are condensed. The cooled secondary effluent flows from cooler 214 through conduit 215 to gas-liquid separator 216.

In gas-liquid separator 216 the uncondensed portion of the secondary effluent comprising hydrogen and C₁ to C₃ hydrocarbons and a portion of the hydrogen derivatives of contaminants in the secondary feed such as ammonia, separates from the condensed portion of the secondary effluent. The uncondensed portion of the secondary effluent flows from separator 216 through conduit 217 to means 281 for removal of ammonia and then through conduit 282 to an absorber (not shown) where the uncondensed secondary effluent is contacted with a mixture of hydrocarbons to be decontaminated. In the absorber light hydrocarbons are extracted from the uncondensed secondary effluent while oxygen and deposit precursors are extracted from the hydrocarbon mixture to be decontaminated. From the absorber the uncondensed secondary effluent flows to the refinery fuel system.

The condensed portion of the secondary effluent separated in gas-liquid separator 216 from the uncondensed secondary effluent flows from separator 216 through pipe 218 to the suction side of pump 219. The condensed secondary effluent, i.e., secondary condensate, is discharged by pump 219 into pipe 220. The secondary condensate flows through pipe 220 to heat exchanger 212 as described hereinbefore. From heat exchanger 212 the secondary condensate flows through pipe 221 to splitter 222. In splitter 222 an overhead comprising hydrogen and C₁ to C₅ hydrocarbons together with all or a portion of C₆ hydrocarbons depending upon local operating demands together with the residual ammonia and hydrogen sulfide is taken overhead through conduit 223 to cooler 224. In cooler 224 the overhead is cooled to a temperature at which C₄ and heavier hydrocarbons are liquid. From cooler 224 the splitter overhead flows through conduit 225 to accumulator 226. From accumulator 226 the uncondensed splitter overhead flows through conduit 262 to the refinery fuel gas main. The condensed splitter overhead flows from accumulator 226 through pipe 227 to the suction side of pump 228. Pump 228 discharges the condensed splitter overhead into pipe 229 through which the condensed splitter overhead flows to splitter 222 for use as reflux. That portion of the condensed splitter overhead in excess of requirements for reflux in splitter 222 is diverted through pipe 230 under control of valve 231 to pipe 232 and light naphtha storage, further processing, distribution, etc.

A minor portion of the bottoms of splitter 222 flows to a reboiler system comprising pipe 233, heat exchanger 234 and pipe 235 or any other means can be employed for maintaining a temperature in splitter 222 at which hydrocarbons having five to six carbon atoms, as desired, are volatile. The balance, and major portion, of the splitter bottoms substantially devoid of ammonia flows from splitter 222 through pipe 236 to the suction side of pump 237. Pump 237 discharges into pipe 238 through which the splitter bottoms flows to coil 239 in heater 240. While the splitter bottoms are substantially devoid of ammonia and hydrogen sulfide the nitrogen content thereof is nevertheless considerably greater than 1 p.p.m. Accordingly, the splitter bottoms having a nitrogen content up to about 140 p.p.m. is mixed with about 50 to about 95 parts by volume of a mixture of hydrocarbons having a low nitrogen content such that when mixed with the splitter bottoms in the proportions set forth hereinbefore the nitrogen content of the mixture is not greater than about 7 p.p.m. A suitable low nitrogen mixture of hydrocarbons, designated nitrogen-free hydrocarbon mixture, is straight run naphtha containing not more than about 0.5 p.p.m. of nitrogen.

The nitrogen-free mixture of hydrocarbons, i.e., con-

taining not more than about 0.5 p.p.m. is drawn from a source not shown through pipe 241 by pump 242 and discharged into pipe 243 at a pressure higher than the pressure in pipe 238. The nitrogen-free hydrocarbon mixture flows through pipe 243 to heat exchanger 244 where the nitrogen-free hydrocarbon mixture is in indirect heat exchange relation with effluent from primary decontaminator 249 flowing through conduit 259. From heat exchanger 244 the nitrogen-free mixture of hydrocarbons flows through pipe 245 to a point in pipe 233 intermediate to pump 237 and to heater 240. The mixture of splitter bottoms and nitrogen-free hydrocarbon mixture, hereinafter designated primary feed, flows through pipe 238 to coil 239 in heater 240. In heater 240 the mixture is heated to a reaction temperature within the range of about 600° to about 850° F. From coil 239 the heated primary feed flows through conduit 246 to primary hydrodecontaminator 249. At a point in conduit 246 intermediate to heater 240 and to decontaminator 249 hydrogen-containing gas, e.g., hydrogen-rich reformer gas is mixed with the primary feed in an amount to provide about 250 to about 2500 s.c.f. of hydrogen per barrel of primary feed to provide a primary feed mixture.

The primary feed mixture flows downwardly through primary decontaminator 249 which is charged with particle-form solid hydrogenating and hydrodesulfurizing and hydrodenitrogenizing catalyst such as a mixture of oxides of cobalt and molybdenum. The reaction products, designated primary effluent, flow from primary decontaminator 249 through conduit 250 to heat exchanger 244 where the primary effluent is in indirect heat exchange relation with the nitrogen-free hydrocarbon mixture as described hereinbefore. From heat exchanger 244 the primary effluent flows through conduits 251 and 252 to heat exchanger 253 where the primary effluent is in indirect heat exchange relation with the primary condensate flowing from pump 264 through pipe 265. From heat exchanger 253 the primary effluent flows through conduit 254 to cooler 255 where the primary effluent is cooled to a temperature at which under the existing pressure C_4 and heavier hydrocarbons are condensed. The cooled primary effluent flows from cooler 255 through conduit 256 to gas-liquid separator 257. In gas-liquid separator 257 the uncondensed portion of the primary effluent separates from the condensed portion of the primary effluent. The uncondensed portion of the primary effluent, designated recycle gas, flows from separator 257 through conduits 258 and 259 to means 260 for removing ammonia. The recycle gas substantially devoid of, i.e., containing not more than about 0.02 percent by volume of ammonia flows from means 260 for removing ammonia through conduits 261 and 269 to conduit 207 for admixture with the nitrogenous hydrocarbon mixture as described hereinbefore.

The condensed primary effluent, designated primary condensate, flows from separator 257 through pipe 263 to the suction side of pump 264. Pump 264 discharges the primary condensate into pipe 265 through which the primary condensate flows to heat exchanger 253 where the primary condensate is in indirect heat exchange relation with the primary effluent as hereinbefore described. From heat exchanger 253 the primary condensate flows through pipe 265a to splitter 266.

In splitter 266 the temperature is maintained to take overhead through conduit 267 a splitter overhead comprising hydrogen, C_1 - C_4 hydrocarbons and C_5 and C_6 hydrocarbons dependent upon other facilities, e.g., for isomerizing the C_5 and C_6 hydrocarbons. The splitter overhead flows through conduit 267 to cooler 268 where the splitter overhead is cooled to a temperature at which C_4 and heavier hydrocarbons are liquid. From cooler 268 the cooled splitter overhead flows through conduit 269 to accumulator 270. In accumulator 270 the uncondensed splitter overhead separates from the liquid splitter

overhead and flows through conduit 271 to the refinery fuel main. The condensed splitter overhead flows through pipe 272 to the suction side of pump 273. Pump 273 discharges the splitter overhead condensate into pipe 274 through which the splitter overhead condensate flows to splitter 266 for use as reflux. Splitter condensate in excess of that required for reflux in splitter 266 is diverted through pipe 275 under control of valve 276 to further processing, e.g., separation of C_5 and C_6 and isomerization thereof, storage, distribution, etc.

The major portion of the splitter bottoms containing not more than 1 p.p.m. of nitrogen flows from splitter 266 through pipe 280 to a reformer unit (not shown) as feed thereto. A minor portion of the splitter bottoms flows through a reboiler comprising pipe 277, heat exchanger 278 and pipe 279 or other means for heating the minor portion of the splitter bottoms to a temperature such that the components of the aforesaid splitter overhead are volatilized.

A further embodiment of the present invention is illustrated by the flowsheet FIGURE 4. A nitrogenous hydrocarbon mixture (as defined hereinbefore) is drawn from a source not shown through pipe 301 by pump 302 and discharged into pipe 303 at a pressure sufficient to drive the nitrogenous hydrocarbon mixture through the equipment intermediate to pump 302 and to secondary decontaminator 309. From pump 302 the nitrogenous hydrocarbon mixture flows through pipe 303 to heat exchanger 304 where the nitrogenous hydrocarbon mixture is in indirect heat exchange relation with the secondary effluent flowing from secondary decontaminator 309 through conduit 310. From heat exchanger 304 the nitrogenous hydrocarbon mixture flows through pipe 305 to coil 306 in heater 307. In heater 307 the nitrogenous hydrocarbon mixture is heated to a reaction temperature within the range of about 600° to about 850° F. From heater 307 the heated nitrogenous hydrocarbon mixture flows through pipe 308 to conduit 332 and thence to secondary decontaminator 309.

In conduit 332 the heated nitrogenous hydrocarbon mixture is mixed with hydrogen-containing gas in amount to provide about 500 to about 2500 s.c.f. of hydrogen per barrel of nitrogenous hydrocarbon mixture. A hydrogen-containing gas for this purpose can be hydrogen-rich reformer gas flowing through conduit 331 from a source not shown at the pressure greater than the pressure in secondary decontaminator 309. Hydrogen-containing gas from stripper 321 flowing therefrom through conduits 325 and 326 to means 327 for the removal of ammonia and thence through conduit 328 under control of valve 329 to compressor 374 and conduit 375 to conduits 331 and 332 is likewise suitable. A mixture of both of the aforesaid hydrogen-containing gases can be used. The mixture of nitrogenous hydrocarbon mixture and hydrogen-containing gas flows through conduit 332 to secondary decontaminator 309. The aforesaid mixture flows downwardly through secondary decontaminator 309 which contains a bed of catalyst having hydrogenating, hydrodesulfurizing, and hydrodenitrogenizing capabilities. From secondary decontaminator 309 the reaction products, designated secondary effluent, flow through conduit 310 to heat exchanger 304 where the secondary effluent is in indirect heat exchange relation with the nitrogenous hydrocarbon mixture as described hereinbefore. From heat exchanger 304 the secondary effluent flows through conduit 311 to heat exchanger 312 where the secondary effluent is in indirect heat exchange relation with secondary condensate flowing from gas-liquid separator 316 through pipe 317 to pump 318 and thence through pipe 319 to heat exchanger 312. From heat exchanger 312 the secondary effluent flows through conduit 313 to cooler 314 where the secondary effluent is cooled to a temperature at which, under the existing pressure C_4 and heavier hydrocarbons are condensed. From cooler 314 the cooled

secondary effluent flows through conduit 315 to gas-liquid separator 316.

In gas-liquid separator 316 the uncondensed secondary effluent separates from the condensed secondary effluent. The uncondensed secondary effluent, designated primary stripping gas, leaves separator and flows by way of conduits 333, 334 and 372 to stripper 335 and primary decontaminator 346.

The condensed secondary effluent, designated secondary condensate, flows from separator 316 through pipe 317 to the suction side of pump 318. Pump 318 discharges into pipe 319 through which the secondary condensate flows to heat exchanger 312. In heat exchanger 312 the secondary condensate is in indirect heat exchange relation with the secondary effluent as described hereinbefore. From heat exchanger 312 the secondary condensate flows through pipe 320 to stripper 321.

In stripper 321 the secondary condensate is contacted with stripping gas such as hydrogen-containing gas, e.g., reformer gas flowing from conduit 331 through conduit 347 under control of valve 348. A stripper overhead comprising hydrogen, ammonia, hydrogen sulfide and a major portion of C_4 and lighter hydrocarbons flows through conduits 325 and 326 to a means 327 for removal of ammonia and thence through conduit 370 to an absorber not shown where the stripper overhead is contacted with a hydrocarbon mixture to extract C_4 and heavier hydrocarbons from the stripper overhead and to extract water and deposit precursors from the hydrocarbon mixture. The stripper overhead flows from the absorber to the refinery fuel gas main.

A portion or all of the stripper overhead can be diverted from conduit 370 through conduit 328 under control of valve 329 to compressor 374. Compressor 374 discharges the stripper overhead through conduits 375, 331 and 332 for admixture with the nitrogenous hydrocarbon mixture as described hereinbefore.

A minor portion of the stripper bottoms flows through a reboiler comprising pipe 322, heat exchanger 323 and pipe 324 or any other means whereby a temperature is maintained in stripper 321 at which the aforescribed overhead is produced.

The balance, and major portion, of the stripper bottoms flows from stripper 321 through pipe 336 to the suction side of pump 337. Pump 337 discharges into pipe 338. The stripper bottoms flowing through pipe 338 contain not more than 140 p.p.m. of nitrogen. At some point in pipe 338 the stripper bottoms is mixed with a hydrocarbon mixture having a low nitrogen content, i.e., not more than about 5 p.p.m. of nitrogen in the proportion of about 50 to about 95 parts of low nitrogen hydrocarbon mixture, designated nitrogen-free hydrocarbon mixture, to about 50 to about 5 parts of stripper bottoms to provide a primary decontaminator feed naphtha containing not more than 7 p.p.m. of nitrogen. A suitable nitrogen-free hydrocarbon mixture is a straight run naphtha containing about 2 p.p.m. of nitrogen.

Such a nitrogen-free hydrocarbon mixture is drawn from a source not shown through pipe 341 by pump 342 and discharged into pipe 330. The nitrogen-free hydrocarbon mixture flows through pipe 330 to heat exchanger 343 where the nitrogen-free hydrocarbon mixture is in indirect heat exchange relation with primary effluent flowing from primary decontaminator 346 through conduit 347. From heat exchanger 343 the nitrogen-free hydrocarbon mixture flows through pipe 344 to pipe 338 where it is mixed with the stripper bottoms in the proportions described hereinbefore to provide a primary feed containing not more than about 7 p.p.m. of nitrogen.

The primary feed flows through pipe 338 to coil 339 in heater 340 where the primary feed is heated to a reaction temperature within the range of about 600° to about 850° F. The primary feed flows from heater 340 through conduit 345 to primary decontaminator 346. At some point in conduit 345 intermediate to heater 340 and to

primary decontaminator 346 hydrogen-containing gas is mixed with the primary feed to provide about 250 to about 2500 s.c.f. of hydrogen per barrel of primary feed.

5 A suitable hydrogen-containing gas is stripper overhead flowing from stripper 335 and/or separator overhead flowing from separator 316 through conduits 358, 334 and 361 respectively to means 360 for removal of ammonia and thence through conduit 363 to compressor 364 and conduit 365 to conduit 345.

10 The mixture of primary feed and hydrogen-containing gas, i.e., primary feed mixture flows through conduit 345 to primary decontaminator 346. Primary decontaminator 346 is charged with a particle-form solid hydrogenating and hydrosulfurizing and hydrodenitrogenizing catalyst, e.g., a mixture of oxides of cobalt and molybdenum. The primary feed mixture flows downwardly through primary decontaminator 346. The effluent of primary decontaminator 346, i.e., primary effluent, flows through conduit 347 to heat exchanger 343 where the primary effluent is in indirect heat exchange relation with the nitrogen-free hydrocarbon mixture as described hereinbefore. From heat exchanger 343 the primary effluent flows through conduit 348 to heat exchanger 349 where the primary effluent is in indirect heat exchange relation with the condensate (primary condensate) flowing from separator 353 through pipe 355. From heat exchanger 349 the primary effluent flows through conduit 350 to cooler 351. In cooler 351 the primary effluent is cooled to a temperature at which under the existing pressure C_4 and heavier hydrocarbons are condensed. From cooler 351 the cooled primary effluent flows through conduit 352 to gas-liquid separator 353. In separator 353 the uncondensed primary effluent comprising hydrogen and C_1 to C_8 hydrocarbons flows through conduit 354 to means 377 for removal of ammonia and thence through conduit 378 to an absorber not shown for recovery of light hydrocarbons in hydrocarbon mixture to be treated and removal of water and deposit precursors from the hydrocarbon mixture to be treated. From the absorber the uncondensed primary effluent flows to the refinery fuel main.

15 The condensed primary effluent, i.e., primary condensate, flows through pipe 355 to heat exchanger 349 where the primary condensate is in indirect heat exchange relation with the primary effluent as described hereinbefore. From heat exchanger 349 the primary condensate flows through pipe 356 to stripper 335. In stripper 335 the primary condensate is contacted with a stripping gas, e.g., hydrogen-containing gas, for example, gas from separator 316 and is heated to a temperature at which hydrogen, ammonia, hydrogen sulfide, C_1 to C_3 and a major portion of the C_4 hydrocarbons are volatile. In other words, an overhead comprising hydrogen, ammonia, hydrogen sulfide and a major portion of the C_4 and lighter hydrocarbons is taken overhead. The stripper overhead flows from stripper 335 through conduit 357 to conduit 354 to a means 377 for removal of ammonia and thence through conduit 378 to an absorber not shown. A portion or all of the stripper overhead is diverted from conduit 357 through conduit 358 under control of valve 359 to conduit 361 and thence to means 360 for removal of ammonia.

20 A minor portion of the bottoms of stripper 335 flows through a reboiler comprising pipe 366, heat exchanger 367 and pipe 368 or any other means for maintaining the temperature in stripper 335 required to produce the aforescribed overhead. The major portion (the balance) of the stripper bottoms containing not more than 1 p.p.m. of nitrogen flows through pipe 369 to a reformer.

25 A further embodiment of the present invention is illustrated in FIGURE 5. In FIGURE 5 the flowsheet illustrates the use of the hydrogen-containing gas recovered from the effluent of the secondary decontaminator in the primary decontaminator after removal of ammonia from the uncondensed portion of the secondary effluent. Thus, 75 a nitrogenous mixture of hydrocarbons, as defined here-

inbefore, is drawn from a source not shown through pipe 401 by pump 402. Pump 402 discharges the nitrogenous hydrocarbon mixture into pipe 403 at a pressure sufficient to push the nitrogenous hydrocarbon mixture through the equipment downstream of the pump. The nitrogenous hydrocarbon mixture flows through pipe 403 to heat exchanger 404 where the nitrogenous hydrocarbon mixture is in indirect heat exchange relation with the secondary effluent flowing from secondary decontaminator 409 through conduit 411. The nitrogenous hydrocarbon mixture containing more than 25 p.p.m. of nitrogen flows from heat exchanger 404 through pipe 405 to coil 406 in heater 407. In heater 407 the nitrogenous hydrocarbon mixture is heated to a reaction temperature within the range of about 600° to about 850° F. From heater 407 the heated nitrogenous hydrocarbon mixture flows through conduit 408 to secondary decontaminator 409. At a point in conduit 408 intermediate to heater 407 and to secondary decontaminator 409 hydrogen-containing gas, such as reformer gas, flowing from a source not shown through conduit 410 is mixed with the heated nitrogenous hydrocarbon mixture in the proportion of about 500 to about 2500 s.c.f. per barrel of nitrogenous hydrocarbon mixture to form a secondary charge mixture.

The secondary charge mixture flows downwardly through secondary decontaminator 409 in contact with a hydrogenating, hydrodesulfurizing and hydrodenitrogenizing catalyst such as a mixture of oxides of cobalt and molybdenum. As described hereinbefore, conditions in secondary decontaminator 409 are as follows:

Table V

Catalyst: 2-3 percent cobalt oxide, 9-16 percent molybdenum oxide.
Feed: Nitrogenous hydrocarbon mixture—66 p.p.m. nitrogen.

	Broad	Preferred

Pressure, p.s.i.g.....	200-1,000	400-800
S.c.f. H ₂ /barrel of feed.....	500-2,500	800-1,000
Space velocity, v./hr./v.....	1-10	2.5-5

The effluent from secondary decontaminator 409, designated secondary effluent, flows through conduit 411 to heat exchanger 404 where the secondary effluent is in indirect heat exchange relation with the nitrogenous hydrocarbon mixture as described previously herein. From heat exchanger 404 the secondary effluent flows through conduit 412 to heat exchanger 413 where the secondary effluent is in indirect heat exchange relation with secondary condensate drawn from gas-liquid separator 417 flowing through pipe 422 to pump 423 and discharged into pipe 424 by pump 423. From heat exchanger 413 the secondary effluent flows through conduit 414 to cooler 415 where the secondary effluent is cooled to a temperature at which C₄ and heavier hydrocarbons are condensed. The cooled secondary effluent flows from cooler 415 through conduit 416 to gas-liquid separator 417. In gas-liquid separator 417 the uncondensed secondary effluent separates from the condensed secondary effluent. The uncondensed secondary effluent flows through conduit 418 to means 419 for removal of ammonia. The secondary effluent containing not more than about 0.02 percent by volume ammonia, now designated primary hydrogenating gas, flows from means 419 for removal of ammonia through conduit 420 to conduit 421 where it is mixed with the mixture of the bottoms of splitter 426 and the nitrogen-free hydrocarbon mixture to form a primary charge mixture as described hereinafter.

The condensed secondary effluent flows from gas-liquid separator 417 through pipe 422 to the suction side of pump 423. The condensed secondary effluent, designated secondary condensate, is discharged by pump 423 into pipe 424 through which the secondary condensate flows to heat exchanger 413. In heat exchanger 413 the sec-

ondary condensate is in indirect heat exchange relation with the secondary effluent as previously described herein. From heat exchanger 413 the secondary condensate flows through pipe 425 to splitter 426. In splitter 426 a temperature is maintained at which residual hydrogen, hydrogen derivatives of nitrogen and sulfur, C₁ to C₅ hydrocarbons with or without C₆ hydrocarbons dependent upon the local auxiliary facilities (e.g., isomerizing facilities) are taken overhead and C₆ and heavier hydrocarbons form a bottoms. The aforesaid overhead is taken from splitter 426 through conduit 427 to cooler 428 where the splitter overhead is cooled to a temperature at which C₄ and heavier hydrocarbons are liquid. From cooler 428 the splitter overhead flows through conduit 429 to accumulator 430. In accumulator 430 the uncondensed splitter overhead separates from the condensed splitter overhead and is vented through conduit 431 to the refinery fuel gas main. The splitter overhead condensate, i.e., condensed splitter overhead, is drawn from accumulator 430 through pipe 432 by pump 433. Pump 433 discharges the splitter condensate into pipe 434. A portion of the splitter condensate flows through pipe 436 under control of valve 437 to splitter 426 for use as reflux. The balance of the splitter condensate, in excess of that required for reflux in splitter 426, flows through pipe 435 to further processing or storage and/or distribution as light naphtha.

A minor portion of the bottoms of splitter 426 flows through a reboiler comprising pipe 438, heat exchanger 439 and pipe 440 or any other suitable means for heating a portion of the splitter bottoms to a temperature required to maintain a temperature in splitter 426 at which the aforescribed splitter overhead is produced.

The balance, and major portion, of the splitter bottoms containing not more than about 140 p.p.m. nitrogen is drawn from splitter 426 through pipe 441 by pump 442 and discharged into pipe 443. In order to produce an effluent from primary decontaminator 446 containing not more than 1 p.p.m. of nitrogen under the conditions set forth hereinbefore it is necessary that the hydrocarbon charge to primary decontaminator 446 contain not more than about 7 p.p.m. of nitrogen. Accordingly, the splitter bottoms containing not more than about 140 p.p.m. of nitrogen is mixed with about 50 to about 95 parts by volume of a mixture of hydrocarbons boiling preferably in the gasoline range containing an amount of nitrogen such that when mixed with the splitter bottoms in the proportions set forth hereinbefore the mixture contains not more than about 7 p.p.m. of nitrogen. Suitable proportions of splitter bottoms having various nitrogen concentrations and nitrogen-free hydrocarbon mixtures to be mixed therewith to provide a primary feed containing not more than about 7 p.p.m. of nitrogen are listed in Table VI.

Table VI

Splitter Bottoms		Nitrogen-Free Hydrocarbon mixture		Primary Feed, P.p.m. of N
P.p.m. of N	Volumes	P.p.m. of N	Volumes	
140	5	0.2	95	7.2
100	5	2.0	95	6.8
50	10	2.2	90	7.0
45	5	5.0	95	7.0
25	20	2.5	80	7.0
12	50	2.0	50	7.0

A suitable nitrogen-free hydrocarbon mixture or diluent is straight-run naphtha containing not more than 5.0 p.p.m. of nitrogen. Accordingly a nitrogen-free hydrocarbon mixture containing nitrogen not in excess of that which when mixed with the splitter bottoms in a proportion within the range of 95 to 50 volumes per 5 to 50 volumes of splitter bottoms to form a primary feed con-

taining not more than about 7 p.p.m. of nitrogen is drawn from a source not shown through pipe 447 by pump 448. Pump 448 discharges the nitrogen-free hydrocarbon mixture or diluent into pipe 477 at a pressure at least equal to that in pipe 443. The nitrogen-free hydrocarbon mixture or diluent flows through pipe 477 to heat exchanger 449 where the nitrogen-free hydrocarbon diluent is in indirect heat exchange relation with primary effluent flowing from primary decontaminator 446 through conduit 451. From heat exchanger 449 the nitrogen-free hydrocarbon diluent flows through pipe 450 to pipe 443. In pipe 443 the nitrogen-free hydrocarbon diluent is mixed with the splitter bottoms to form a primary feed containing not more than about 7 p.p.m. of nitrogen. The primary feed flows through pipe 443 to coil 444 in heater 445. In heater 445 the primary feed is heated to a reaction temperature within the range of about 600° to about 850° F. The heated primary feed flows from heater 445 through conduit 421 to primary decontaminator 446. At some point in the conduit 421 hydrogen-containing gas containing not more than about 0.02 percent ammonia, e.g., hydrogen-containing gas from gas-liquid separator 417 is mixed with the primary feed in a proportion within the range of about 250 to about 2500 s.c.f. per barrel of primary feed to form a primary charge mixture. The primary charge mixture flows downwardly through primary decontaminator 446 in which the conditions are within the ranges set forth in Table VII.

Table VII

Catalyst: 2 to 3 percent cobalt oxide, 9 to 16 percent molybdenum oxide.
Feed: Not more than about 7 p.p.m. of nitrogen.

	Broad	Preferred
Temperature, ° F.	600- 850	675-775
Pressure, p.s.i.g.	200-1,000	400-500
Hydrogen, S.c.f./b., of Primary Feed	250-2,500	400-600
Space Velocity, v./hr./v.	1- 10	2.5-5.0

The effluent from primary decontaminator 446, designated primary effluent, flows through conduit 451 to heat exchanger 449 where the primary effluent is in indirect heat exchange relation with the nitrogen-free hydrocarbon diluent or mixture as previously described herein. From heat exchanger 449 the primary effluent flows through conduit 452 to heat exchanger 453 where the primary effluent is in indirect heat exchange relation with the primary condensate flowing from gas-liquid separator 457. From heat exchanger 453 the primary effluent flows through conduit 454 to cooler 455 where the primary effluent is cooled to a temperature such that C₄ and heavier hydrocarbons are condensed. From cooler 455 the cooled primary effluent flows through conduit 456 to gas-liquid separator 457. In gas-liquid separator 457 the uncondensed primary effluent is separated from the condensed primary effluent.

In separator 457 the uncondensed primary effluent is vented through conduit 458 to means 478 for removal of ammonia and thence through conduit 479 to an absorber (not shown) where it is contacted with a hydrocarbon mixture which absorbs C₄ and heavier hydrocarbons. At the same time the uncondensed primary effluent removes water and deposit precursors from the hydrocarbon mixture. The uncondensed primary effluent flows from the aforesaid absorber to the refinery fuel gas main.

The condensed portion of the primary effluent designated primary condensate flows from gas-liquid separator 457 through pipe 459 to heat exchanger 453 where the primary condensate is in indirect heat exchange relation with the primary effluent as described hereinbefore. From heat exchanger 453 the primary condensate is drawn through pipe 460 by pump 461 which discharges the primary condensate into pipe 462. The primary condensate flows through pipe 462 to splitter 463.

In splitter 463 an overhead comprising hydrogen, ammonia, hydrogen sulfide, C₁ to C₄ hydrocarbons, and C₅ and C₆ hydrocarbons dependent upon auxiliary facilities locally available is taken through conduit 464. For example, in some refineries it can be preferred to take all of the C₅ and C₆ hydrocarbons overhead for isomerization. Therefore, the splitter overhead can be characterized as comprising hydrogen, ammonia, hydrogen sulfide, and hydrocarbons the major portion of which are C₅ and lighter hydrocarbons. The overhead from splitter 463 flows through conduit 464 to cooler 465 where the C₄ and heavier hydrocarbons are condensed. From cooler 465 the splitter overhead flows through conduit 466 to accumulator 467. In accumulator 467 the uncondensed splitter overhead is vented to the refinery fuel gas main through conduit 468. The condensed splitter overhead is drawn from accumulator 467 through pipe 469 by pump 470. Pump 470 discharges the condensed splitter overhead into pipe 471. A portion of the condensed splitter overhead required for reflux flows through pipe 471 under control of valve 472 to splitter 463. The balance flows through pipe 473 to storage, further processing, or distribution as light naphtha.

A minor portion of the splitter bottoms is circulated through a re-boiler comprising pipe 474, heat exchanger 475 and pipe 476 or any other suitable means for heating the minor portion of the bottoms to a temperature such that the temperature required to produce the aforescribed splitter overhead is maintained in splitter 463.

The balance, and major portion, of the splitter bottoms flows from splitter 463 through pipe 480 to a reformer unit (not shown) employing a nitrogen-sensitive reforming catalyst. It will be noted that the splitter bottoms flowing through pipe 477 contains not more than 1 p.p.m. of nitrogen.

In view of the foregoing discussion of the illustrative examples of the present invention it is manifest that the present invention provides for hydrodecontaminating a reformer charge stock containing more than 25 p.p.m. of nitrogen in the presence of a catalyst having hydrogenating and decontaminating capabilities such as a mixture of oxides of cobalt and molybdenum under conditions of temperature, pressure, space velocity and hydrogen to charge stock ratio to produce a secondary condensate. The secondary condensate is stripped of volatile hydrogen derivatives of the contaminants originally present in the charge stock to provide a partially decontaminated secondary decontaminator bottoms containing not more than about 140 p.p.m. of nitrogen. The secondary decontaminator bottoms containing not more than about 140 p.p.m. of nitrogen is mixed with reformer charge stock to provide a primary decontaminator feed containing not more than about 7 p.p.m. of nitrogen. The primary decontaminator feed is then hydrodecontaminated in the presence of a catalyst having hydrogenating and decontaminating capabilities and in the presence of hydrogen containing gas containing not more than about 0.02 percent ammonia under conditions of temperature, pressure, space velocity and ratio of hydrogen to primary decontaminator feed to produce, after fractionating the primary decontaminator condensate, a reformer feed containing less than about 1 p.p.m. of nitrogen.

The hydrodecontaminating conditions used in both the secondary and primary decontaminators are within the limits set forth in Table IV.

Table IV

70	Broad	Preferred
Temperature, ° F.	600 to 850	675 to 775
Pressure, p.s.i.g.	200 to 1,000	400 to 800
S.c.f. H ₂ /bbl. of feed	250 to 2,500	400 to 1,000
Space velocity, v./hr./v.	1 to 10	2.5 to 5.0

We claim:

1. In the method of preparing a hydrocarbon mixture boiling in the boiling range of naphtha and containing in excess of 25 p.p.m. of nitrogen for reforming in the presence of nitrogen-sensitive particle-form solid reforming catalyst wherein a first static bed of nitrogen- and sulfur-insensitive particle-form solid hydrogenating catalytic material is established in a secondary hydrodecontaminator, wherein a second static bed of nitrogen- and sulfur-insensitive particle-form solid hydrogenating catalytic material is established in a primary hydrodecontaminator, wherein a first naphtha containing in excess of 25 p.p.m. of nitrogen is introduced into said secondary hydrodecontaminator and intimately contacted therein with the aforesaid first static bed of hydrogenating catalytic material at a liquid hourly space velocity in the range of about 1 to about 10, wherein hydrogen is introduced into said secondary hydrodecontaminator and flows therethrough at a rate in the range of about 500 to about 2500 s.c.f. per barrel of the aforesaid first naphtha, wherein in hydrodecontaminating conditions of temperature in the range of about 600° to about 850° F. and a total pressure of about 200 to about 1000 p.s.i.g. are maintained in the aforesaid secondary hydrodecontaminator, wherein a secondary hydrodecontaminator effluent comprising ammonia, hydrogen sulfide, hydrogen, and C₁ and heavier hydrocarbons is withdrawn from said secondary hydrodecontaminator, wherein the whole of said secondary hydrodecontaminator effluent is mixed with a second naphtha having a relatively low concentration of organic nitrogen compounds and containing also impurities in the form of organic sulfur compounds to form a primary hydrodecontaminator feed, said second naphtha being a major portion of the normally liquid hydrocarbons of said primary hydrodecontaminator feed, wherein said primary hydrodecontaminator feed is introduced into the aforesaid primary hydrodecontaminator and intimately contacted therein with the aforesaid second static bed of hydrogenating catalytic material at a liquid hourly space velocity in the range of about 1 to about 10 in the presence of hydrogen in a ratio in the range of about 250 to about 2500 s.c.f. per barrel of naphtha, wherein hydrodecontaminating conditions of a temperature in the range of about 600° to about 850° F., and of a total pressure in the range of about 200 to about 1000 p.s.i.g. are maintained in said primary hydrodecontaminator, wherein a primary hydrodecontaminator effluent comprising ammonia, hydrogen sulfide, hydrogen, and C₁ and heavier hydrocarbons is withdrawn from said primary hydrodecontaminator, wherein said primary hydrodecontaminator effluent is separated into a plurality of fractions, wherein one of the aforesaid fractions is a C₅+ hydrocarbon fraction of substantially reduced nitrogen content, and wherein in said C₅+ hydrocarbon fraction is reformed in contact with nitrogen-sensitive particle-form solid reforming catalyst to produce reformer effluent comprising C₁ and heavier hydrocarbons and hydrogen, wherein said reformer effluent is separated into reformer recycle gas and reformer make-gas each comprising C₁ to C₃ hydrocarbons and hydrogen, and reformate comprising C₄ and heavier hydrocarbons, and wherein at least a portion of said reformer make-gas is introduced into said secondary hydrodecontaminator, the improvement which comprises separating the aforesaid secondary hydrodecontaminator effluent into at least one gaseous fraction comprising ammonia, hydrogen sulfide, hydrogen and C₁ to C₃ hydrocarbons, and a liquid fraction comprising C₄ and heavier hydrocarbons containing not more than 140 p.p.m. of nitrogen, and mixing the aforesaid liquid fraction only

with the aforesaid second naphtha to provide a liquid primary hydrodecontaminator fed containing not more than 7 p.p.m. of nitrogen.

2. The method set forth in claim 1 wherein the gaseous fraction separated from the secondary hydrodecontaminator effluent is treated to remove ammonia, and wherein at least a portion of the so-treated gaseous fraction is introduced into the secondary hydrodecontaminator.

3. The method set forth in claim 1 wherein a gaseous fraction comprising ammonia, hydrogen sulfide, hydrogen, and C₁ to C₃ hydrocarbons is separated from the primary hydrodecontaminator effluent, wherein ammonia is removed from the aforesaid gaseous fraction, and wherein the aforesaid gaseous fraction after said removal of ammonia is introduced into said primary hydrodecontaminator.

4. The method set forth in claim 1 wherein the gaseous fraction separated from the secondary hydrodecontaminator effluent is treated to remove ammonia, wherein at least a portion of the so-treated gaseous fraction is introduced into the secondary hydrodecontaminator, wherein a gaseous fraction comprising ammonia, hydrogen sulfide, hydrogen, and C₁ to C₃ hydrocarbons is separated from the primary hydrodecontaminator effluent, wherein in said gaseous fraction is treated to remove ammonia, and wherein the so-treated gaseous fraction is introduced into said primary hydrodecontaminator.

5. The method set forth in claim 1 wherein a gaseous fraction comprising ammonia, hydrogen sulfide, hydrogen, and C₁ to C₃ hydrocarbons is separated from the primary hydrodecontaminator effluent, wherein said gaseous fraction is treated to remove ammonia, and wherein said treated gaseous fraction and reformer make-gas are introduced into said primary hydrodecontaminator.

6. The method set forth in claim 1 wherein a gaseous fraction comprising ammonia, hydrogen sulfide, hydrogen, and C₁ to C₃ hydrocarbons is separated from the primary hydrodecontaminator effluent, wherein at least a portion of the reformer make-gas is mixed with the aforesaid separated gaseous fraction to provide diluted primary hydrodecontaminator gaseous fraction, wherein a gaseous fraction comprising ammonia, hydrogen sulfide, hydrogen, and C₁ to C₃ hydrocarbons is separated from the secondary hydrodecontaminator effluent, wherein said separated gaseous fraction of secondary hydrodecontaminator effluent is mixed with a portion of said diluted primary hydrodecontaminator gaseous fraction to provide diluted secondary hydrodecontaminator gaseous fraction wherein the balance of the aforesaid diluted primary hydrodecontaminator gaseous fraction is treated to remove ammonia, wherein in said treated diluted primary hydrodecontaminator gaseous fraction is introduced into said primary hydrodecontaminator, wherein said diluted secondary hydrodecontaminator gaseous fraction is treated to remove ammonia, and wherein at least a portion of said treated diluted secondary hydrodecontaminator gaseous fraction is introduced into said secondary hydrodecontaminator.

7. The method set forth in claim 6 wherein at least one of the group consisting of the diluted primary hydrodecontaminator gaseous fraction and the diluted secondary hydrodecontaminator gaseous fraction is treated to remove hydrogen sulfide.
